UNITED STATES PATENT OFFICE.

HENRY D. JONES, OF SPRINGFIELD, OHIO, ASSIGNOR TO THE KELLY-SPRINGFIELD ROAD ROLLER COMPANY, OF SPRINGFIELD, OHIO, A CORPORATION OF OHIO.

TOOL FOR SCARIFYING DEVICES.

1,236,311.

Specification of Letters Patent.

Patented Aug. 7, 1917.

Application filed November 11, 1916. Serial No. 130,863.

To all whom it may concern:

Be it known that I, HENRY D. JONES, a citizen of the United States, residing at Springfield, in the county of Clark and 5 State of Ohio, have invented certain new and useful Improvements in Tools for Scarifying Devices, of which the following is a specification.

This invention relates to scarifying devices for road engines, and more particularly relates to an improvement in the tools employed in connection with such devices for breaking or tearing up the ground.

In scarifying attachments of a certain 15 type it has been common to employ tools in the form of spikes arranged at the end of tool holders or drag bars such for instance as illustrated in my pending application Ser. No. 35,839 filed June 23rd, 1915. While 20 these spikes are effective for certain characters of work, yet for certain purposes it is desirable that a tool be provided which will have a comparatively large clearance space.

25 The object of this invention is to provide a tool of this character which can be readily attached to the drag bars or tool holders employed in connection with the spike type of tool so that either form of tool may be 30 substituted for the other without disturbing the other parts of the scarifying devices.

In the accompanying drawings:—

Figure 1 is a side elevation of a drag bar or tool holder showing my new form of tool

35 applied thereto.

Fig. 2 is a top plan view of the same.

Fig. 3 is an end view of the tool holder.

Fig. 4 is an end view of the tool.

In the said drawings, 1 represents the tool 40 holder or drag-bar, one end of which is provided with an integrally formed split collar 2 by which it may be attached to the pivoted draft bar in the usual way and on its upper edge there is an integrally formed split collar 3 by which it is attached to a cross shaft 45 by means of which the holder may be raised and lowered and pressure applied thereto by the fluid pressure device such as illustrated in my application referred to. The rear or 50 free end of the tool holder is preferably bifurcated, the bifurcated portions having V-shaped notches to receive the spike type of tool referred to, which is square in cross section, caps with V-shaped notches being 55 employed for securing the spikes in position

to the tool holder. For this purpose the tool holder is provided with four perforated bosses 4, corresponding to perforated bosses in the cap by which the spikes may be clamped firmly in position as shown clearly 60 in my former application referred to.

In the present case the tool 6 is provided with a series of perforated bosses 7, corresponding to the bosses 4 so that it may be readily attached to the tool holder by the 65 same bolts 5 formerly employed. The tool is also preferably provided with V-shaped ribs 8 which fit the V-shaped notches 9 of the holder to lend further strength to the connection between the tool and holder. The 70 tool is of arched or horse-shoe form so that a large clearance space is provided to allow the material torn up by the tools to be readily cleared therefrom, it having been found necessary to provide for this in cer- 75

By the arrangement described it will be seen that the scarifying attachment may be provided with two sets of tools of different characters which may be readily removed 80 and applied without any changes whatever in the other parts of the scarifying mechanism. By this construction, also scarifying attachments which have already been put into use equipped with the spike type of 85 tool may be supplied with the new form of tool which may be readily applied to it at the established points of attachment for the spikes.

Transversely arranged recess shown in 90 Fig. 1 is especially adapted to a tool holder of the character heretofore described in that it affords means for forcing the tool from the holder and also enables tool holders to be formed with an improved seat formed 95 by the longitudinally arranged recess since the center part does not constitute any bearing surface for the tool, but the tool in fact gets its bearing from the end parts of the holder.

The tool shown in the present case is one which is especially designed to act as a rooter plow, although the invention is also applicable to scarifying tools of other forms.

Having thus described my invention, I 105 claim:

In a scarifying device, a combination tool holder provided at its free end with a vertically arranged V-shaped recess and also provided with a plurality of openings for 110

attaching points at each side of said recess, and a tool having a V-shaped vertical rib projecting beyond the body of the same and shaped to fit said recess and also formed with openings at each side of said rib, registering with the openings in said holder, said holder being also provided with a trans-

versely arranged recess extending beyond the vertically arranged recess.

In testimony whereof, I have hereunto set my hand this 6th day of November, 1916.

HENRY D. JONES.

Witness:

CHAS. I. WELCH.
